UNITED STATES PATENT OFFICE

PAUL C. HELLER, OF LA LIMA, HONDURAS

ENGINE

Application filed January 18, 1928. Serial No. 247,664.

This invention relates to an engine, the general object of the invention being to provide an oscillatory member eccentrically mounted in a circular chamber and actuated by the exploding gases or other propelling force, with means for rotating an eccentric by the movement of said member, said eccentric being connected to the driven shaft.

Another object of the invention is to provide a plurality of members for dividing the chamber into a number of compartments which receive the impelling fluid, with shoes on the inner ends of the members engaging the oscillatory member, with yieldable means for keeping the shoes in engagement with the oscillatory member.

Another object of this invention is to subdivide the explosions of a large volume of gases into small impacts rapidly following each other, without the necessity of construction of a plurality of expensive and delicate parts, as individual cylinders, connecting rods, pistons and bearings.

A further object is to reduce the local stresses of high pressure by sub-dividing into small individual compartments, which receive said pressure successively and thus permit reduction of the weight and material necessary to build up a high powered engine.

Another object is to provide a perfectly balanced engine whereby all eccentrically moving parts are counterpoised by similar parts of same weight, without resorting to fly wheels, counterweights or other devices which have otherwise no useful function.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a vertical sectional view through the improved device the section being taken on line 1—1 of Figure 2.

Figure 2 is a sectional view on line 2—2

of Figure 1, showing two units connected with the same shaft.

As shown in these views, 1 indicates a circular casing, through the center of which passes the shaft 2 to be driven, said shaft being journaled in the sides of the casing by means of the anti-friction bearings 3. A ring-shaped partition 4 is arranged in the casing and an oscillatory member 5 of circular shape is eccentrically mounted in the chamber formed by the partition 4. A disk 6 is eccentrically connected with the shaft 2 and ball bearings 7 are placed between the disk and the inner wall of the member 5. A wear ring 8 is fastened to the outer circumference of the member 5 by being shrunken thereon or otherwise fastened thereto.

A plurality of telescopic partition forming members 9 are slidably arranged in packing glands 10 arranged in the partition 4, shoes 11 being pivoted to the inner ends of such members and such shoes engaging the plate 8. The outer parts 9' of the telescopic members have their outer ends bearing against the inner circumference of the casing 1 and each telescopic member has each part thereof made hollow so as to receive spring means 9'' which tend to hold the inner parts with the shoes pressed against the member 5. The side edges of the inner parts of the telescopic members fit in a fluid-tight manner in grooves 12 formed in the sides of the casing. These telescopic members, as will be seen, divide the crescent-shaped chamber formed by the member 5 and partition 4 into a plurality of separate compartments which receive the explosive mixture or other impelling fluid from the inlet manifold 13, the inlet ports 14 of which are controlled by the movement of the member 5, as the port 14 of each compartment will not be opened until the member 5 is in such a position as to make said chamber its full size.

The member 5 and the casing are provided with the holes 15 through which a cooling medium may pass.

Figure 2 shows a compressor and engine connected together, the exhaust ports 16 of the compressor being connected by the passages 17 with the inlet ports 14' of the engine.

The exhaust manifold of the engine is shown at 18. With this arrangement, the first device can be used as a blower or compressor and the explosions can occur in the second device.

As will be seen, the propelling force in each compartment acts on the member 5 to move it tangentially and this movement of member 5 tends to rotate the eccentric disk 6 which 10 is connected with the shaft 2, so that said shaft 2 is rotated.

Attention is called to the fact that the member 5 does not rotate, but has a substantially oscillatory movement in the chamber formed 15 by the partition 4. In other words, the top part of this member 5 remains at the top throughout the movement of said member. As the member uncovers the inlet ports 14, air or carbureted air, according to which form of 20 ignition system is being used, flows into the compartments, the ports of which are uncovered, and then this air is compressed by the further movement of the member 5. The compression increases as the size of the compartments is reduced by the movement of the 25 member 5 until the member reaches a position where the compartment A, for instance, in Figure 1 is reduced to its smallest extent. The firing of the mixture in this chamber 30 then takes place, which causes the member to move tangentially to the left in Figure 1, so that the chamber B is reduced to its smallest extent and then the firing of the mixture in this chamber takes place, which causes the 35 member to move to a position where the chamber C is reduced to its smallest extent and the charge in this chamber C fired. The explosions follow each other in rapid succession 40 and occur always at or near the highest point of compression. When the carbureted air is drawn into the compartments, the device must be equipped with spark plugs, one for each compartment, but when air is drawn into the compartments, means must be provided for 45 injecting fuel into the compartments after the air is fully compressed so that the heat of the compressed air will ignite the fuel. As both of these ignition systems are well known, it is not thought necessary to describe them 50 in detail or illustrate them.

As the member 5 moves, the chambers opposite to those in which the charge is being ignited, will be of full size so that the inlet ports will be opened and either air or carbureted air will be forced into such chambers 55 and this flow of air will force the burnt gases from the chambers, due to the fact that the exhaust ports are also open, as the exhaust ports are in alignment with the inlet ports. 60 Then during the further movement of the member 5, both the inlet and exhaust ports will be closed and the air will be compressed, as before described. Thus the device works on the two-cycle principle, with the member 5 acting as a common piston for all of the

compartments. When two of the devices are coupled together, as in Figure 2, the right device acts as a compressor for the air, this air being held in the first device until the ports 14' are uncovered by the movement of the 70 member 5 in the second device, and this air will rush into the compartments of the second device, expelling the burnt gases therefrom, and then this air will be further compressed in the second device and finally the charge will 75 be ignited either by spark plugs or by fuel injected into the heated compressed air.

It is thought from the foregoing description that the advantages and novel features of my invention will be readily apparent. 80

It is to be understood that I may make changes in the construction and in the combination and arrangement of the several parts, provided that such changes fall within the scope of the appended claims. 85

What I claim is:—

1. An apparatus of the class described comprising a circular cylinder, a ring-shaped partition therein forming a circular chamber, a shaft passing through the center of the cylinder and rotatably mounted therein, an eccentric disk fastened to the shaft, a non-rotatable circular member eccentrically arranged in the chamber and having a central opening therein for receiving the eccentric 90 disk, a plurality of radially arranged members passing through openings in the partition, each member being telescopic, with its outer part abutting the inner circumferential wall of the casing, shoes pivoted to the inner parts and bearing against the outer circumference of the circular member, means for yieldingly holding the telescopic members expanded, the side walls of the chamber having 95 grooves therein for receiving the edges 100 of the inner parts of the telescopic members and inlet and exhaust means connected with the compartments formed by the telescopic members and the walls of the chamber. 105

2. An apparatus of the character described comprising a circular casing, a shaft journaled centrally therein, spaced partitions arranged centrally of the casing, and dividing the latter into spaced parallel compartments, 110 a ring-shaped partition arranged in each compartment, an oscillatory circular member eccentrically mounted in each ring-shaped partition on said shaft and eccentrically mounted with relation to each other, slideable 115 telescopic members dividing the casing and one of said ring-shaped partitions into a plurality of compartments, shoes pivoted to the inner sections of said members and bearing against the outer circumference of the adjacent oscillatory member, means for yieldingly holding the telescopic members expanded, 120 inlet and exhaust ports for said compartments, and means establishing communication between the exhaust ports of the com- 125 130

parts of one ring-like partition with the inlet ports of the adjacent ring-like partition and controlled by the movements of the oscillatory member in the latter mentioned partition.

⁵ In testimony whereof I affix my signature.

PAUL C. HELLER.
